P. GRABLER,
GARMENT SUPPORTER,
APPLICATION FILED SEPT 29, 1919.

1,368,335.

Patented Feb. 15, 1921.

Inventor,
Peter Grabler
By Brockell & Hyde
Attest.

UNITED STATES PATENT OFFICE.

PETER GRABLER, OF LAKEWOOD, OHIO.

GARMENT-SUPPORTER.

1,368,335.

Specification of Letters Patent. Patented Feb. 15, 1921.

Application filed September 29, 1919. Serial No. 327,270.

To all whom it may concern:

Be it known that I, PETER GRABLER, a citizen of the United States, residing at Lakewood, in the county of Cuyahoga and State 5 of Ohio, have invented certain new and useful Improvements in Garment-Supporters, of which the following is a specification.

This invention relates to garment supporters and particularly to that type of such devices utilized by men for supporting trousers.

More specifically the invention relates to the combination of shoulder straps connected by a pair of co-extensive tapes, a garment member comprising strap portions also connected by co-extensive tapes and a connector comprising a main frame for receiving the tapes of the garment member 20 and provided with a friction roller engaging one of the tapes of the shoulder straps and another frame swiveled about the axis of the first roller and provided itself with a roller adapted to engage the other tape 25 of the shoulder strap. The construction produces great flexibility in the connecting device itself and great yielding capacity in the shoulder straps and their tapes.

This invention may be further briefly 30 summarized as consisting in the construction of parts hereinafter set forth in the following description, drawings, and claims.

Referring to the drawings, Figure 1 is a perspective view of a portion of a garment 35 supporter constructed according to my invention; Fig. 2 is a detail view of the connector; Fig. 3 is a side view of the connector; and Fig. 4 is a sectional view.

In the drawings, 1 and 2 represent the 40 shoulder straps which are provided with co-extensive tapes 3 and 4 at the rear. The garment member comprises strap portions 5 and 6 which in like manner are provided with co-extensive tapes 7 and 8. The tapes 45 of both the shoulder straps are adjustably connected by a connector which comprises a main frame preferably formed of wire and comprising side portions 9, and a lower straight bar member 10 for receiving the tapes 7 and 8. Eyes 11 are arranged at the upper ends of the side portions 9 and they engage inwardly extending portions 12 arranged in parallelism with the bar member 10 and providing a shaft for a roller 13 50 which is engaged by the tape 4 of the shoulder straps. Forming a part of the inwardly

extending portions 12 are side portions 14 extending upwardly therefrom and united to form a cross bar portion 15 for receiving a friction roller 16. The parts 12, 14 and 15 60 also form a frame. The friction roller 16 is engaged by the loop 3 of the shoulder straps.

It will be seen from the foregoing that when the supporter is in use the garment member may move freely about the portion 65 10 of the main frame according to the various positions which the wearer assumes. The tapes passing from this portion 10 also form a swivel for it. It will further be seen that the tapes of the shoulder straps in passing over the friction rollers are permitted to move back and forth thereon and to swivel 70 about the same. It will also be seen that the linked tandem arrangement of the frames permits it to yield and accommodate itself to 75 the various movements of the wearer.

The bar 10 may be provided with a roller similar to the roller 13.

My particular connector may be used either on the front or the rear of the garment supporter, as may be desired.

Having described my invention, I claim:

1. In a garment supporter, the combination of shoulder engaging means, garment engaging means, tapes secured to one of said means, and a connector comprising a main frame, a second frame swiveled to said main frame, a roller rotatably mounted upon said connector about the axis of said swivel connection, and a second roller rotatably 85 mounted on said second frame in parallel relation to said first named roller, said rollers being engaged by said tapes and said second frame being engaged by the other of 90 said engaging means.

2. In a garment supporter, the combination of garment engaging means, shoulder engaging means, tapes secured to one of said means, a connector between said tapes and the other of said engaging means comprising a pair of frame members having swivel connection with each other, one of said frame members being engaged by said tapes, while the other frame member is engaged by the other of said engaging means, said frame 100 members bearing extended relation with each other when in operative position.

3. In a garment supporter, the combination of garment engaging means, shoulder engaging means, tapes secured to one of said 110 means, and a connector between said tapes and the other of said engaging means, com-

prising a plurality of parallel bars, adjacent bars being fixed with relation to each other, while another of said bars is swivelly connected with respect to said fixed bars, rollers 5 rotatably mounted upon said adjacent bars and being engaged by said tapes, and the other bar being engaged by the other of said engaging means.

4. A connector for garment supporters, 10 comprising a main frame of substantially U-shape, a second frame of substantially rectangular shape, said main frame having its ends swivelly connected to one of the stretches of said second named frame, a 15 roller rotatably mounted upon said second named frame and extending between the

ends of said U-shaped frame, and a second roller rotatably mounted upon the other stretch of said second named frame.

5. A connector for garment supporters, 20 comprising a frame of substantially U-shape, a second frame having a bar parallel to the closed end of said U-shaped frame, said first named frame having its ends swivelly connected to said second named frame, a 25 roller rotatably mounted upon said connector about the axis of the swivel connection between said frame members, and another roller rotatably mounted upon the bar of said second frame. 30

In testimony whereof I affix my signature.
PETER GRABLER.
